UNITED STATES PATENT OFFICE.

CHARLES F. RICHARDSON AND MARK S. FERGUSON, OF KOKOMO, INDIANA.

CAR FENDER OR GUARD.

1,424,590.

Specification of Letters Patent. Patented Aug. 1, 1922.

Application filed December 28, 1921. Serial No. 525,408.

To all whom it may concern:

Be it known that we, CHARLES F. RICHARDSON and MARK S. FERGUSON, citizens of the United States, residing at Kokomo, in the county of Howard and State of Indiana, have invented certain new and useful Improvements in Car Fenders or Guards, of which the following is a specification.

This invention appertains to certain improvements in fenders or guards for power operated vehicles, and more particularly to an automatic type of such fenders or guards adapted for use on street cars and the like.

The principal object of the invention is to provide for a fender or guard of the class set forth, and one designed for automatic operation upon striking a person or object in the path of the vehicle to prevent the person or object from coming in contact with the wheels of the vehicle, and at the same time will cause the actuation of the control devices of the vehicle in a manner to bring the latter rapidly to a full stop.

With the foregoing and other objects in view, the invention resides in the certain new and useful construction, arrangement and operation of parts, as will be herein-after more fully described, set forth in the appended claims, and illustrated in the accompanying drawings, in which:

Figure 1 is a fragmentary side elevation, partly in section, of the forward portion of a railroad car or the like, and showing a preferred embodiment of the invention as applied thereto,

Fig. 2 is a front elevation thereof,

Fig. 3 is a vertical transverse section taken on the line 3—3 of Fig. 1,

Fig. 4 is a perspective view of the improved fender or guard per se, and,

Fig. 5 is a vertical section through the valve to be actuated, upon the operation of the fender or guard, for effecting the emergency application of the brakes of the vehicle or car.

Referring to the drawings, wherein similar characters of reference designate corresponding parts throughout the several views thereof, the preferred form of fender or guard to which the present invention is to be applied, and as shown, consists of a trip buffer or fender 10 pivotally depending from a shaft 11 journaled in brackets 12 and 13, which are disposed in transverse alinement at the extreme forward end of the vehicle or car body 14, and this trip fender 10 is

connected to a vertical arm 15 disposed medially of a second fender or life guard 16, by means of a two part reach rod comprising a short arm portion 17 rigidly fastened to the shaft 11, and pivotally connected, as at 18, to the forward end of a longer arm portion 19, which has pivotal connection, as at 20, with the said vertical arm 15. The second fender or life guard 16 is mounted on a shaft 21 journaled in brackets 22 and 23 dependingly secured in transverse alinement at the under side of the vehicle or car body 14, at a distance in rear of the trip fender 10. A foot lever or plunger 24 is passed downwardly of the floor of the vehicle 14, and is pivoted at its lower end to a lever arm 25, which is rigidly secured to the shaft 11, whereby, after the trip fender 10 has been struck by a person or object and has swung in a rearward direction for the actuation of the second fender or life guard 16 to lowered position, the engineer or operator in charge of the vehicle or car will restore the parts to normal position by pressing downwardly upon the foot lever or plunger 24 for the purpose, a coiled spring 26 being connected at one end to the upper end of the vertical arm 15, of the second fender or life guard 16, and at its other end to the under side of the vehicle or car body 14, in a manner to facilitate the quick lowering of the fender or guard 16 to its operative position.

In the accomplishment of the desired objects and purposes of the present invention, it is contemplated to secure on the trip fender shaft 11, by means of a set screw or the like 27, a lever arm 28 having pivotal connection, as at 29, within the forward bifurcated end 30 of a reach rod or arm 31, which has its rear end portion upwardly bent, preferably on a curved line as shown, and the free end of this curved portion is pivoted, as at 32, to a lever arm 33 mounted on the free end of a valve body 34 carried within a valve casing 35. The valve casing 35 is preferably threaded to or otherwise secured on the air pipe line 37 leading to the brake mechanism of the vehicle or car 14, so that upon a partial rotation of the valve body 34 within the same, the ports 36 of the latter will open the brake pipe line 37 to atmosphere to allow for the setting of the brakes (not shown) in the ordinary manner of operation thereof. It is to be here noted that the reach rod or arm 31 may also have

connection with a control switch or the like (not shown), whereby the power may be cut off from the driving motor or motors of the vehicle or car simultaneously with the 5 operation of the valve 35 for the emergency operation of the brake mechanism thereof.

In the operation of the device in the installation of the same as shown, the trip fender 10 is normally set in substantially vertical depending position, when the second fender or life guard 16 will be held in its raised position by the tensioning action of the coiled spring 26, and the valve 35 will be closed, so that the brakes of the vehicle 10 or car are set for operation upon the opening of the air line 37 to atmosphere. In the event of the trip fender 10 coming in contact with the body of a person or an object 15 on the road or trackway, the same will be swung in the rearward direction, and will break the pivotal connection 18 between the parts 17 and 19 of the reach rod connecting the trip fender 10 with the second fender or life guard 16, in an upward direction, when 20 the coiled spring 26 will pull or tilt the latter in a forward direction, so that its forward free edge will be lowered to within a relatively short distance above the surface 25 of the road or trackway, when the body of the person or object having passed under the trip fender 10 will be lifted onto the fender or guard, or otherwise prevented from being run over by the leading wheels of the vehicle or car.

The rearward swinging movement of the member 10 rotates the shaft 11 and causes the arm 28 thereof to pull on the reach rod or arm 31 in a forward direction, which actuates the lever arms 33 for imparting an 35 efficient rotary movement to the valve body 34 for the opening of its ports 36 to atmosphere, when the air line 37 will be bled of the air pressure therein, and the brake mechanism set for emergency application of 40 the brakes of the vehicle or car. Upon the vehicle or car coming to a full stop, and the removal of the body or object from the second fender or life guard 16, the latter and the trip fender 10, together with the valve 35 45 will be restored to normal position, ready for a repeat operation thereon, by the engineer or operator in charge of the vehicle or car pressing downwardly on the foot lever or plunger 24, and thereby breaking the pivotal connection 18 of the reach rod parts 17 and 19 in a downward direction, and again placing the spring 26 under tension.

From the foregoing, it will be readily apparent that the invention provides for 60 an extremely simplified construction and arrangement of the fender actuated brake, or brake and power controlled means, and one out of the control of the operator of the vehicle or car so as to be 65 entirely automatic in operation, and which

is highly effective and efficient not only in the saving of a life of a person, or the value of an object, by preventing the same from being run over by the wheels of the vehicle or car, but also in bringing the 70 vehicle or car to an immediate stop, whereby to greatly lessen the possible chance for serious injury or damage to the person or object, such as might otherwise obtain should the vehicle or car be permitted to 75 continue its travel after the person or object has been struck thereby and caught up by the second fender or life guard.

It is well understood that, while a preferred embodiment of the fender and brake or power operating means connected therewith has been described and illustrated herein in specific terms and details of construction, arrangement, and operation, various changes in and modifications of the same 85 may be resorted to without departing from the spirit of the invention, or the scope of the claims appended hereto.

Having thus fully described the invention, what is claimed, is;—

1. A car fender comprising a pivoted buffer normally disposed in vertical position, a fender member arranged rearwardly thereof, an extensible and contractible element having one end anchored and its other end attached to said member for normally tending to lower said fender, a reach rod formed of a short and a long section, pivotally connected together, said elongated section attached to said member and said short section attached to said buffer and providing means when the sections are disposed in lengthwise alinement to maintain said buffer vertical and said fender elevated against the action of said element, until 95 said sections are swung on their pivots by the shifting of the buffer rearwardly, whereby the fender member is lowered by the action of said element.

2. A car fender comprising a pivoted buffer normally disposed in vertical position, a fender member arranged rearwardly thereof, an extensible and contractible element having one end anchored and its other end attached to said member for normally tending to lower said fender, a reach rod formed of a short and a long section, pivotally connected together, said elongated section attached to said member and said short section attached to said buffer and providing 110 means when the sections are disposed in lengthwise alinement to maintain said buffer vertical and said fender elevated against the action of said element, until said sections are swung on their pivots by the shifting of the buffer rearwardly, whereby the fender member is lowered by the action of 115 said element, and a foot operated means for returning the buffer, reach rod and member 120 to normal position.

3. A car fender comprising a pivoted buffer normally disposed in vertical position, a fender member arranged rearwardly thereof, an extensible and contractible element having one end anchored and its other end attached to said member for normally tending to lower said fender, a reach rod formed of a short and a long section, pivotally connected together, said elongated section attached to said member and said short section attached to said buffer and providing means when the sections are disposed in lengthwise alinement to maintain said buffer vertical and said fender elevated against the action of said element, until said sections are swung on their pivots by the shifting of the buffer rearwardly, whereby the fender member is lowered by the action of said element, and means projecting rearwardly from the buffer for throwing into operation the braking means of a car when the buffer is shifted rearwardly.
4. A car fender comprising a pivoted buffer normally disposed in vertical position, a fender member arranged rearwardly thereof, an extensible end contractible element having one end anchored and its other end attached to said member for normally tending to lower said fender, a reach rod formed of a short and a long section, pivotally connected together, said elongated section attached to said member and said short section attached to said buffer and providing means when the sections are disposed in lengthwise alinement to maintain said buffer vertical and said fender elevated against the action of said element, until said sections are swung on their pivots by the shifting of the buffer rearwardly, whereby the fender member is lowered by the action of said element, and means projecting rearwardly from the buffer for throwing into operation the braking means of a car when the buffer is shifted rearwardly.

5. A car fender comprising a pivoted buffer normally disposed in vertical position, a fender member arranged rearwardly thereof, an extensible and contractible element having one end anchored and its other end attached to said member for normally tending to lower said fender, a reach rod formed of a short and a long section, pivotally connected together, said elongated section attached to said member and said short section attached to said buffer and providing means when the sections are disposed in lengthwise alinement to maintain said buffer vertical and said fender elevated against the action of said element, until said sections are swung on their pivots by the shifting of the buffer rearwardly, whereby the fender member is lowered by the action of said element, and means for returning the buffer, reach rod and member to normal position, and means projecting rearwardly from the buffer for throwing into operation the braking means of a car when the buffer is shifted rearwardly.

In testimony whereof, we affix our signatures hereto.

CHARLES F. RICHARDSON.
MARK S. FERGUSON.
